UNITED STATES PATENT OFFICE.

FREDERICK SHRIVER, OF GRAND RAPIDS, MICHIGAN.

STEAM-GENERATOR.

SPECIFICATION forming part of Letters Patent No. 250,008, dated November 22, 1881.

Application filed April 21, 1881. (No model.)

To all whom it may concern:

Be it known that I, FREDERICK SHRIVER, of Grand Rapids, in the county of Kent and State of Michigan, have invented a new and Improved Steam-Generator, of which the following is a full, clear, and exact description.

The object of this invention is to provide a steam-generator which has the base-burning feature embodied in it, and which is designed 10 for low-pressure heating purposes and for domestic work, and which has no tube or crown-sheet to protect by a fixed water-line.

The invention consists of an upright boiler of **U**-shaped cross-section, having a double 15 shell inclosing the water-space, curved in such a manner that one shell or wall forms the exterior of the boiler and the walls of the interior central fuel-reservoir, while the other and concentric shell forms the walls of the interior 20 smoke-flue of the boiler, through which pass the heat and products of combustion, thereby forming an interior and an exterior water-chamber connected with each other.

Figure 1 is a vertical sectional elevation of 25 the improved boiler on line *xx*, Fig. 2. Fig. 2 is a transverse section of the same on line *yy*, Fig. 1.

Similar letters of reference indicate corresponding parts.

30 In the drawings, **A** represents the boiler, having a double shell, **B C**, that is of **U**-shaped cross-section, inclosing a water-space, **D**. The opening or space between the shells or walls **B C** is closed at bottom and top with corresponding **U**-shaped heads **E**, to which said shells or walls **B C** are secured in the usual manner by rivets **a**. The boiler-shells **B C** are shaped in such a manner that in effect an interior water-chamber, **R**, and an exterior water-chamber, **L**, are formed, which connect with each other at the opposite curves or points of the **U** to form the water-space **D**. When the said shells are inclosed in a brick wall, **F**, or otherwise, the shell **B** forms a central space, **G**, 45 that serves as a magazine for fuel, and the shell **C** forms a space, **H**, through which the products of combustion pass into the smoke-stack **I**. **K** represents an opening in the exterior of the boiler **A** opposite the fuel-feed opening **L'**, and 50 an opening, **K'**, through the surrounding brick-

work **F**, which is designed to be provided with a damper, gives access to the space **H** for clearing the same at any time. Around this opening **K** the boiler-shells **B C** are riveted to a frame, **K'**, inserted between them.

55

M represents the fire-chamber, provided with grate **M'**, and surrounded with a cylindrical water-jacket, **N**, whose water-space **N'** is closed at top and bottom by heads or rings **E'**, in the same manner as is shown in the boiler **A**.

60

O represents an opening in the water-jacket **N**, to give access to the fire on the grate **M'**.

The boiler **A** and water-jacket **N** are of the same diameter, and the two are locked or keyed together, the boiler **A** resting on the water-jacket **N**, by the tongues **d** of the lower head, **E**, entering corresponding grooves **c** in the top ring, **E'**, of the water-jacket **N**. The device is thus strengthened also by this tongued and grooved joint **c d**, which joint could also be made with the tongue and groove beveling or **V**-shaped, instead of rectangular, as shown. The boiler **A** and water-jacket **N** are further held together and a constant circulation of water maintained 65 between them by means of the exterior circulating-pipes, **P**, that connect the bottom of the boiler with the upper part of the water-jacket **N**.

70

A plate, **Q**, fixed at an angle of about forty-five degrees beneath the fuel-feed opening **L'**, serves to direct the fuel that is fed into the 80 device upon the grate **M'**.

The boiler **A** is covered with a metal plate, **A'**, which closes the space **G** and a portion of the space **H** at the top, and said cover **A'** has a rib, **f**, on its under side, that engages in a corresponding groove, **g**, formed in the top head, **E**, whereby a tight joint is made and the boiler **A** also stiffened or strengthened.

85

R' represents the steam-escape pipe from the boiler **A**. This boiler **A** can be used without 90 the water-jacket **N**, a brick fire-pot being substituted therefor, in either case it being designed to have a suitable brick ash-pit in which the grate **M'** is to be supported.

Having thus described my invention, I claim 95 as new and desire to secure by Letters Patent—

1. In a steam-generator, a boiler having a double shell curved in such a manner that one shell forms the exterior wall of the boiler and the wall of the central fuel-reservoir, while the 100

other shell forms the walls of the interior smoke-flue, substantially as and for the purpose set forth.

2. In a steam - generator, the combination, 5 with the shell B, forming the exterior of the boiler and the inner wall of the fuel-magazine, and the shell C, forming the walls of the smoke or fire flue, of the U-shaped heads E, substantially as herein shown and described.
- 10 3. In a steam-generator, the combination,

with the boiler A, consisting of the shells B C, curved as shown and described, and provided with the rear exterior opening, K, opposite the fuel-feed opening L', of the rear opening, K', in the surrounding brick wall, as and for the purpose set forth. 15

FREDERICK SHRIVER.
